Primary Examiner — Catherine A Tuttle**CLAIM**

The ornamental design for a reversible fidget toy, as shown and described.

DESCRIPTION

FIG. 1 is a front and top perspective view of a reversible fidget toy, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the reversible fidget toy that form no part of the claimed design.
